UNITED STATES PATENT OFFICE.

HENRY A. AINSWORTH, OF MOLINE, ILLINOIS, ASSIGNOR TO WILLIAMS, WHITE & CO., OF SAME PLACE.

DROP-HAMMER.

SPECIFICATION forming part of Letters Patent No. 363,351, dated May 24, 1887.

Application filed March 1, 1887. Serial No. 229,297. (No model.)

To all whom it may concern:

Be it known that I, HENRY A. AINSWORTH, of Moline, in the county of Rock Island and State of Illinois, have invented certain new and useful Improvements in Drop-Hammers, of which the following is a specification.

My invention relates to drop-hammers; and it consists in the combination, with the hammer and a lifting-strap therefor, of elevating-rollers having a bearing-face composed wholly or in part of paper or equivalent material.

The invention further consists in the combination, with the elevating-rollers thus constructed, of a hammer provided with a metallic, preferably steel, strap arranged to pass between the rollers.

Heretofore it has been customary to employ in machines of this class cast-iron rollers, which were arranged to press upon both sides of a wooden strap passing upward between them; but such plan is objectionable for the reason that in a comparatively short time the wood splinters and slivers off, and renders the strap useless, because of its decreased strength and thickness, the rollers, as a rule, being capable of approaching each other a limited distance only. Furthermore, in applying pressure upon the strap by means of or through the metallic rollers the latter, or some portion of the frame-work directly or indirectly connected therewith, are liable to be strained and broken, this being especially true where the hammer-head is heavy and considerable pressure is required to be applied to its strap to elevate it.

To overcome these objections to prior constructions is the object of my invention.

Referring to the accompanying drawings, Figure 1 is a perspective view of my improved drop-hammer, and Figs. 2 and 3 views illustrating the construction of the rollers.

Referring to the drawings, A indicates the press as a whole, which may be of any desired construction, except as to the features hereinafter set forth and claimed; and B indicates the hammer-head, free to slide vertically in or upon guides or ways thereon. This hammer is provided at its upper end with a flat metallic strap, C, which will by preference be made of steel, thereby insuring strength, light-

ness, and durability. This strap passes upward between the elevating-rollers D D', as is usual, one of the rollers, D, being carried in fixed bearings, while the other, D', is mounted in a pivoted yoke, E, as shown.

Upon the shaft F of each roller is a gear-wheel, G, the gears on each roller meshing and giving uniform rotation thereto, one of the shafts being furnished with a band-pulley, as usual, to receive motion from any convenient source.

The rollers D D' may be made up in various ways—that is to say, they may be composed of a series of disks clamped between metallic end plates, as shown in Fig. 2; or they may be made by winding the paper about the roller-shaft until a roll of the required size is built up, as shown in Fig. 3. Instead of either of these plans the roller may be made of papier-maché compressed in a hydraulic press to the desired size and form. I do not, however, restrict myself to any particular method or manner of building up the bearing-surfaces of these rollers, as it is a matter that may be varied considerably without departing from the spirit of my invention.

While paper or papier-maché will give just the degree of elasticity desired, and will present a surface admirably adapted to act upon the metal strap, I do not limit myself to its use, but mean to include in my claims any equivalent material, such as leather, real or artificial, and like fibrous substances.

The rollers herein described may be used in connection with the ordinary wood hammer-straps heretofore used, if desired; and it will be seen that under this combination the wood will not splinter or sliver off, as the bearing-faces of the rollers are somewhat elastic or yielding, and while they press against the strap with sufficient force to elevate the hammer, the strap will not be mashed or crushed out of shape, as happens when metallic rollers are used. I prefer, however, to use the steel strap for the reason that it is stronger, lighter, and more durable, and is not as liable to injure the face of the rollers as the wooden strap.

Having thus described my invention, what I claim is—

1. In a drop-press, the combination, with a

100

hammer and its strap, of the elevating-rollers D D', provided with bearing-faces of paper or its equivalent.

2. In a drop-press, the combination, with a hammer and the metallic strap secured thereto, of the rollers D D', provided with bearing-faces of paper or its equivalent.

3. In a drop-press, the combination, with a hammer and its strap, of the elevating-rollers provided with yielding or elastic bearing-faces.

4. The combination, in a drop-press, of a supporting-frame, a hammer-head mounted

and arranged to slide therein, a steel lifting-strap attached to the hammer-head and extending upward therefrom, and paper-faced rolls bearing against opposite faces of said strap, substantially as set forth. 15

In witness whereof I hereunto set my hand in the presence of two witnesses.

HENRY A. AINSWORTH.
